UNITED STATES PATENT OFFICE.

GEORGE M. WILLIS, OF CHICAGO, ILLINOIS.

MEANS FOR SEPARATING BITUMEN FROM BITUMEN-BEARING ORE.

No. 918,629.

Specification of Letters Patent.

Patented April 20, 1909.

Application filed January 7, 1908. Serial No. 409,716.

To all whom it may concern:

Be it known that I, GEORGE M. WILLIS, a citizen of the United States, residing at Chicago, in the county of Cook and State of Illinois, have invented a certain new and useful Improvement in Means for Separating Bitumen from Bitumen-Bearing Ore, of which the following is a full, clear, concise, and exact description, reference being had to the accompanying drawings, forming a part of this specification.

The object of my invention is to provide an improved means for separating bitumen from bitumen bearing ore. Heretofore it has been proposed to accomplish this result in two general ways: First, to mix the ore, preferably in a pulverized condition, with a solvent adapted to extract the bitumen from the ore and to then run off the liquid, leaving the impurities behind. The solution is then distilled, leaving the bitumen in solid form, and by condensing the solvent it may be used repeatedly. Second, by mixing the pulverized ore with water and boiling and agitating it so as to separate the impurities from the bitumen.

My invention belongs to the second class above mentioned, and heretofore difficulty has been experienced in the use of apparatus for this purpose in that it has been very difficult to handle the pulverized ore without having it cake into lumps that were practically unworkable. Also, it has been difficult to form a mixture divided finely enough to facilitate the separation of the sand, silt and impurities generally, from the bitumen, and further it has been difficult to perfectly eliminate the moisture from the mixture after the precipitation of the impurities.

My system for accomplishing the result indicated consists in pulverizing the ore in the presence of hot water, washing the pulverized ore by means of a stream of hot water to a first pan in which the mixture of water and pulverized ore is boiled by the application of heat to the pan and a part of the impurities are thereby separated and precipitated, transferring the mixture of hot water, bitumen and remaining impurities to a second similar pan in which it is again boiled and stirred, or agitated, and more of the impurities are separated and precipitated, transferring the bitumen and remaining impurities and water intimately associated with the same to an inclined pan or chute heated sufficiently to evaporate all the moisture and

liquefy but not burn the bitumen. In this fluid condition, the bitumen is run into settling tanks, and after a short time the remaining impurities settle and collect at the bottom.

It has been found that all bitumen bearing ore contains besides a small percentage of bitumen, a large percentage of comparatively coarse particles of silica or sand and a small percentage of impalpable powder, as silt or decomposed silicates or carbonates, and also some moisture. In my system, I make use of hot water for the purpose of keeping the rolls of the pulverizer clean and maintaining the pulverized particles of bitumen separated at all times, since these particles will not cohere nor adhere to any wet surfaces when surrounded by water films. As a result, the large percentage of silica grains are readily separated, especially when agitated in the second pan, and by the time the bitumen leaves the second pan all of the larger particles of foreign matter heavier than water are separated and removed from the bitumen. The water, however, serves to intimately associate the impalpable powder with the bitumen particles, and this association can only be destroyed by wholly eliminating the moisture and rendering the bitumen fluid, which I accomplish as described and which permits the silt to settle in the settling tank and the resulting purified bitumen may be drawn off from the top of this tank.

In a co-pending application, Serial No. 364,821, filed March 27, 1907, applicant has disclosed and claimed the process of accomplishing the results herein set forth.

The several drawings illustrating my invention are as follows:

Figure 1 shows diagrammatically in top view the separating and drying pans, and the means I employ to transfer the material from one pan to another; Fig. 2 shows in side view the parts shown in Fig. 1; Fig. 2^a shows in side view a settling tank in position at the lower end of the inclined pan; Fig. 3 is an enlarged sectional view taken along the line 3—3 in Fig. 1; Fig. 4 is a sectional view taken along the line 4—4 in Fig. 3; Fig. 5 is an enlarged sectional view taken along the line 5—5 in Fig. 1; Fig. 6 is an enlarged sectional view taken along the line 6—6 in Fig. 2; Fig. 7 is a sectional view taken along the line 7—7 in Fig. 6.

Referring to the drawings, 1 is a hopper

adapted to feed the ore to the crushing rolls 2 and 8, and finally therethrough to the pulverizing rolls 9, 9. Water is run upon the rolls 9, 9 by means of nozzles 10, 10, and as 5 the pulverized material is delivered from the pulverizing rolls it falls into a stream of water delivered from the nozzle 11 into the trough 12. The crushing and pulverizing rolls are arranged to be operated in any suitable 10 manner not shown, and since these rolls and their function form no part of this invention, it is not thought that further description of the same is necessary. By means of this running water the pulverized 15 material is carried along in the trough 12 and into the first pan 13. A chain conveyer or rabble 14 suitably supported upon sprocket wheels 16 and 17 is arranged over the pan 13 so as to feed the material delivered 20 into the pan along to the right. The sprocket wheels 16 are suitably supported upon a shaft, as shown, to which motion is communicated from the pulley 36 by means of the gearing, as indicated. A second chain 25 conveyer 15 is also arranged over the pan 13 and is supported by sprocket wheels 18 and 19 to be driven from pulley 37 through suitable gearing, as indicated, in a direction the reverse of the chain conveyer 14. The function 30 of the paddles carried by the conveyer 14 is to keep the pulverized ore agitated and thoroughly and evenly mixed in the bottom of the pan, to facilitate the separation of the bitumen particles from the coarser impurities, as sand, etc., and to thus permit the bitumen particles to readily become associated with small bubbles of steam formed by the heat applied to the bottom of the pan, by suitable means, as a furnace 21 indicated in Fig. 2. 35

40 The particles of bitumen, as a result of this action, arise to the surface of the liquid and are then fed by means of the skimmers 54, carried by the chain conveyer 15, to the left in the pan 13 and toward the discharge opening 20, through which they pass with more or less of the water from the pan 13 into the second pan 22. Immediately upon entering this pan, the floating bitumen particles and associated impurities come in contact with 45 an agitator 66 supported in a suitable manner above the pan 22 and adapted to be reciprocated transversely to such pan by means of a connecting rod 68 coöperating with a crank 69 secured to and adapted to be 50 driven by a pulley 70 by means of a suitable shaft supported in bearings, as indicated. The agitator 66 carries a number of depending paddles, or teeth, 67, which serve to agitate or stir up the bitumen particles and 55 associated impurities by which the separation of such impurities is facilitated.

60 A belt conveyer 24 is provided in the bottom of the pan 22, being supported upon rollers 25 and 26 and adapted to be moved 65 by means of a pulley 38 through suitable

gearing, as indicated, to move the impurities deposited from the bitumen to the left in the tank and carry them out over the left hand of such tank. A chain conveyer 27 is located over this tank 22 and provided with 70 skimmers adapted to move the floating bitumen particles and impurities still associated therewith to the right in the tank 22, and carry them up the inclined end 23 of such tank, finally delivering them into the 75 inclined pan 30. The conveyer 27 is suitably supported on sprocket wheels 28 and 29 and is adapted to be moved as described by means of a pulley 39 and gearing as indicated. 80

The pan 30 has formed beneath it a flue 31, the lower end of which is in connection with a furnace 32 adapted to supply heat to this flue 31, as a result of which the pan 30 is heated to a temperature considerably above 85 the boiling point of water but not hot enough to carbonize the bitumen particles delivered to such pan. The result of this is that the moisture associated with the bitumen particles is evaporated, and after passing part 90 way down the pan, the moisture is entirely removed and the bitumen particles are melted and collected into liquid form. A chain conveyer 33 supported upon sprocket wheels 34 and 35 is associated with the pan 95 30 to facilitate the motion of the bitumen downward in this pan 30 by means of blades, or paddles, secured to such conveyer. This conveyer is adapted to be operated by means of a pulley 40 through suitable gearing, as 100 indicated, and is entirely inclosed by the sides 41 of the pan 30, which have sectional doors 42 to cover it on top, and thus to a large degree retain the heat communicated to such pan from the flue 31. The fluid 105 bitumen delivered from the pan 30 is collected in a tank 43, shown in Fig. 2^a, and after a suitable interval, the impurities still remaining collect at the bottom, while the purified bitumen remains in liquid condition 110 in the upper part of this tank and may be drawn off through a suitable valve 44 before having cooled sufficiently to become solid. A valve 45 is provided to draw off the impurities from the bottom part of the tank 43. 115

120 Referring to Figs. 3 and 4, the construction of the chain conveyers 14 and 15 and the parts carried thereby will be better understood. The chains 14 are supported by rollers 49 at frequent intervals, from which hangers 48 depend in such a manner as to support a cross-bar 50 a short distance above the bottom of the pan 13. This bar 50 has a number of bosses formed on it through which a number of paddles 51 are 125 adjustably secured, as indicated, in such a way that they may be turned to any desired angle relatively to the bar 50. The hangers 48 are maintained at right angles to the chains 14 by means of braces 57 secured to 130

the chains 14 and having rollers 56 similar to rollers 49.

In practice, the paddles 51 carried by the successive bars 50 are given reverse inclinations relatively, as a result of which the paddles on one bar will move the ore toward one side of the tank and forward a certain extent therein, and the paddles carried by the next bar will move it toward the other side of the tank and still further advance it, but neither will advance the material in the bottom of the tank as rapidly as the motion of the conveyer itself. As a result, the material is slowly advanced through the tank and is maintained in a thoroughly stirred and agitated condition. The motion of the conveyer 14 to the right is very slow in practice in order to permit the heat from the furnace to thoroughly operate upon all of the bitumen particles. The chain conveyer 15 is adapted to be supported at intervals from rails 55 secured to brackets supported from the sides of the tank 13, as indicated, and these bars 52 have secured to them by means of brackets 53 skimmer blades 54, which serve to engage the floating mixture of bitumen particles and associated impurities and move them as described to the left in the tank 13, toward the outlet opening 20.

The detailed construction of the second pan 22 is better understood by reference to Fig. 5, in which the belt conveyer 24 is shown in the lower part of the tank 22 as supported by the rolls 63 which occur at frequent intervals throughout the length of the belt. Deflecting wings 62 are secured to the inside of the tank 22 to direct impurities precipitated from the bitumen upon the belt 24. The chain conveyer 27 is supported from suitable standards 61 by cross-bars 60 by means of rails 59 carried by such standards. These cross-bars occur at frequent intervals, and have attached to them skimmer paddles 58 which serve to move the floating particles of bitumen and the impurities still associated therewith to the right in the tank 22, and finally over into the pan 30. The tank 22 is adapted to be heated in the same manner, as indicated for the tank 13.

Figs. 6 and 7 show in detail the construction of the chain conveyer 33 located in the pan 30, and as indicated the means for supporting these chains 33 consist in scraper blades 46 secured at intervals along the length of the chains 33 and braced therefrom by braces 47 to maintain such scrapers at practically right angles to such chains. The scrapers 46 rest upon the bottom of the pan 30 and serve to move the bitumen particles and remaining impurities toward the lower end of the pan as the moisture is being evaporated from them and as such particles are being liquefied. The pan 30 is inclosed around the conveyer 33 by means of the extended sides 41, and the sectional doors 42

in order that the conveyer and its associated scraper blades 46 may be maintained in warm condition and also that the bitumen may not be decomposed by the action of the heat. I have found in the practice of my invention that by varying the amount of air admitted to the liquid bitumen while it is being dried in the pan 30, varying grades of bitumen may be produced suitable for use in different localities. I have also found in the practice of my invention that it is desirable, if not necessary, to subject the pans 13 and 22 to the direct action of fire in order to thoroughly effect the separation of the bitumen particles from the associated impurities, since the application of heat in other forms, as by steam jackets, etc., has not operated to produce the desired result.

While I have shown my invention in the embodiment described above, I do not, however, limit myself to this construction, but claim any equivalent modification that will suggest itself to those skilled in the art.

What I claim is:

1. As a means for separating bitumen from bitumen bearing ore, a pulverizer for crushing the ore, a water conveyer for conveying the crushed ore to a first pan, a conveyer in such first pan adapted to remove sediment therefrom, a skimmer conveyer for transferring the partly purified bitumen to a second pan adapted to further facilitate the removal of impurities from the bitumen, a conveyer in the second pan adapted to remove sediment therefrom, a skimmer conveyer in the second pan for transferring the bitumen and remaining impurities to a third pan, means for heating the third pan to drive off the moisture and liquefy the bitumen, and a tank for receiving the liquid bitumen. 105

2. As a means for separating bitumen from bitumen bearing ore, a pulverizer for crushing the ore, a water conveyer for conveying the crushed ore to a first pan, means for heating such pan to facilitate the separation of impurities from the bitumen, a conveyer in such pan adapted to remove sediment therefrom, a skimmer conveyer moving more rapidly than such first conveyer and adapted to transfer the partly purified bitumen to a second pan, means for heating such second pan to further facilitate the separation of impurities from the bitumen, a conveyer in such second pan adapted to remove sediment therefrom, a skimmer conveyer in such second pan adapted to transfer the bitumen and remaining impurities to an inclined pan, means for heating such inclined pan to drive off the moisture and liquefy the bitumen, a settling tank for receiving such liquid bitumen, and a conveyer in the third pan for transferring the bitumen and remaining impurities into such tank. 120

3. As a means for separating bitumen 130

from bitumen bearing ore, a pulverizer for crushing the ore, a water conveyer for conveying the crushed ore to a first pan, a conveyer in such first pan adapted to remove sediment therefrom, a skimmer conveyer for transferring the partly purified bitumen to a second pan adapted to further facilitate the removal of impurities from the bitumen, means for agitating the mixture in such second pan, a conveyer in such second pan adapted to remove sediment therefrom, a skimmer conveyer in the second pan for transferring the bitumen and remaining impurities to a third pan, means for heating the third pan to drive off the moisture and liquefy the bitumen, and a tank for receiving the liquid bitumen.

4. As a means for separating bitumen from bitumen bearing ore, a pulverizer for crushing the ore, a water conveyer for conveying the crushed ore to a first pan, a conveyer in such first pan adapted to remove sediment therefrom, a skimmer conveyer for transferring the partly purified bitumen to a second pan, agitating paddles adapted to be reciprocally moved in such second pan to facilitate the further removal of impurities from the bitumen, a conveyer in the second pan adapted to remove sediment therefrom, a skimmer conveyer in the second pan for transferring the bitumen and remaining impurities to a third pan, means for heating the third pan to drive off the moisture and liquefy the bitumen, and a tank for receiving the liquid bitumen.

5. As a means for separating bitumen from bitumen bearing ore, a pulverizer for crushing the ore, a water conveyer for conveying the crushed ore to a first pan, a conveyer in such first pan consisting in a plurality of spades arranged in series on an endless belt and adapted to remove sediment from such first pan, a skimmer conveyer for transferring the partly purified bitumen to a second pan adapted to further facilitate the removal of impurities from the bitumen, a conveyer in the second pan adapted to remove sediment therefrom, a skimmer conveyer in the second pan for transferring the bitumen and remaining impurities to a third pan, means for heating the third pan to drive off the moisture and liquefy the bitumen, and a tank for receiving the liquid bitumen.

6. As a means for separating bitumen from bitumen bearing ore, a pulverizer for crushing the ore, a water conveyer for conveying the crushed ore to a first pan, a conveyer in such first pan consisting in a plurality of angularly adjustable spades arranged in series

on an endless belt and adapted to agitate and remove sediment from such first pan, a skimmer conveyer for transferring the partly purified bitumen to a second pan adapted to further facilitate the removal of impurities from the bitumen, a conveyer in the second pan adapted to remove sediment therefrom, a skimmer conveyer in the second pan for transferring the bitumen and remaining impurities to a third pan, means for heating the third pan to drive off the moisture and liquefy the bitumen, and a tank for receiving the liquid bitumen.

7. As a means for separating bitumen from bitumen bearing ore, a pulverizer for crushing the ore, a water conveyer for conveying the crushed ore to a first pan, a conveyer in such first pan consisting in a plurality of spades supported in series from an endless belt and adapted to move sand and similar material in a coöperating trough, a skimmer conveyer for transferring the partly purified bitumen to a second pan adapted to further facilitate the removal of impurities from the bitumen, a conveyer in the second pan adapted to remove sediment therefrom, a skimmer conveyer in the second pan for transferring the bitumen and remaining impurities to a third pan, means for heating the third pan to drive off the moisture and liquefy the bitumen, and a tank for receiving the liquid bitumen.

8. As a means for separating bitumen from bitumen bearing ore, a pulverizer for crushing the ore, a water conveyer for conveying the crushed ore to a first pan, a conveyer in such first pan consisting in a plurality of angularly adjustable spades supported in series from an endless belt and adapted to move sand and similar material in an associated trough, a skimmer conveyer for transferring the partly purified bitumen to a second pan adapted to further facilitate the removal of impurities from the bitumen, a conveyer in the second pan adapted to remove sediment therefrom, a skimmer conveyer in the second pan for transferring the bitumen and remaining impurities to a third pan, means for heating the third pan to drive off the moisture and liquefy the bitumen, and a tank for receiving the liquid bitumen.

In witness whereof, I hereunto subscribe my name this third day of January, A. D., 1908.

GEORGE M. WILLIS.
